CLAIM

The ornamental design for a light, as shown and described.

DESCRIPTION

FIG. 1 is an isometric view of a light according to the present invention;

FIGS. 2 and 3 are opposite side elevation views of a light according to the present invention;

FIG. 4 is a front elevation view of a light according to the present invention;

FIG. 5 is a rear elevation view of a light according to the present invention;

FIG. 6 is a bottom plan view of a light according to the present invention; and,

FIG. 7 is a top plan view of a light according to the present invention.

The portions of the light shown in broken lines form no part of the claimed design.
